US0D1091276S

(12) **United States Design Patent** (10) **Patent No.:** **US D1,091,276 S**
(45) **Date of Patent:** **** Sep. 2, 2025**

(54) **TORQUE WRENCH**

(71) Applicant: **Atlas Copco Industrial Technique AB**,
Stockholm (SE)

(72) Inventor: **Massimiliano Cattaneo**, Carate Brianza
(IT)

(73) Assignee: **ATLAS COPCO INDUSTRIAL
TECHNIQUE AB**, Stockholm (SE)

(**) Term: **15 Years**

(21) Appl. No.: **29/867,446**

(22) Filed: **Oct. 25, 2022**

(30) **Foreign Application Priority Data**

May 3, 2022 (EM) 009015415

(51) **LOC (15) Cl.** **08-05**

(52) **U.S. Cl.**

USPC **D8/24**

(58) **Field of Classification Search**

USPC D8/24, 107; D10/83

CPC B25B 23/1425

See application file for complete search history.

Assistant Examiner — Benjamin D. Wannemacher

(74) *Attorney, Agent, or Firm* — CANTOR COLBURN
LLP

(57) **CLAIM**

The ornamental design for a torque wrench, as shown and described.

DESCRIPTION

FIG. 1 is a perspective view of a torque wrench, showing my new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side view thereof;

FIG. 7 is a left side view thereof; and,

FIG. 8 is an enlarged view of the portion indicated in FIG. 2.

The dot-dash broken lines of FIGS. 2 and 8 depict the limits of the enlarged view and form no part of the claimed design.

1 Claim, 8 Drawing Sheets
